VOLTAGE-LIMITING ARC INTERRUPTER

Ralph R. Pittman, North Little Rock, Ark.

Application February 19, 1948, Serial No. 9,488

5 Claims. (Cl. 175—30)

1

This invention relates generally to lightning discharge devices of a character adapted for use with electrical circuits for limiting the voltage rise of a conductor by discharging abnormal or superimposed energy to ground and preventing the passage of energy through the discharge device upon attainment of normal electrical conditions.

The present invention is an improvement on the construction described in Patent No. 2,164,720, issued to Ralph R. Pittman, and dated July 4, 1939, and a substitute for abandoned application Serial No. 580,986. In the above-specified patent there is described a tube-filler type of arc extinguishing device in which an arc originates along an abutment line between a tube and a filler eccentrically located therein and the arc is subsequently bodily moved and elongated until extinguished, this functioning being the result of a construction in which the originated arc is initiated across a gap one electrode of which is a conducting member extending upwardly along the abutment line. This is an effective device, despite the fact that the construction is such that peripheral arc movement around the filler cannot be predetermined as to direction clockwise or counterclockwise, and further is substantially limited to $\frac{1}{2}$ the length of the periphery of the filler, or from the originating arc path of greatest restriction to the final or extinguishing path of least restriction. This construction is improved by my invention herein by retaining the desirable features of arc movement and arc elongation, and at the same time making possible the initiation of the arc along a path less restricted than the path along the abutment line, for the reason that lightning current discharged along the path of maximum restriction results in maximum accompanying impact, which must be resisted by providing high strength members.

An object of my invention is to provide, in an arc interrupter embodying an eccentrically located filler within a tube, a construction in which sparkover is caused to occur over a predetermined path which is less restricted than that along the abutment line. An additional object is to provide in such a device means for causing arc movement and accompanying elongation to occur over a predetermined path peripherally of the filler. A further object is to provide a construction in which arc movement around the filler may under certain conditions exceed one-half the peripheral length of the filler.

In general, the arc interrupter of my invention comprises a tubular insulator containing a

2

filler of insulating material so mounted that the filler abuts the insulator along a longitudinal line on the inner wall of the tubular insulator, and conducting members so associated with the filler and insulator as to cause breakdown or sparkover to occur over a predetermined longitudinal path in the space between the filler and the tubular insulator. As the gas generated by the arc moves in a direction away from the abutment line around the filler to a suitably disposed vent, the arc is blown from its originating position and concurrently lengthened, and is thereby extinguished. By means of the construction of my invention, the direction of arc movement may be predetermined, the arc may be caused to originate in any chosen degree of restriction of path, and the extent of peripheral arc movement appreciably increased over that occurring in constructions disclosed in the prior art.

An important advantage of my arc interrupter is the fact that both surge capacity and follow current interrupting ability may be readily adjusted within a substantial range by simply altering the position of the conducting member forming the initiating electrode which causes sparkover to occur over a predetermined path.

My arc interrupter is particularly advantageous for use in a construction in which it is not desired to allow the arc to remain in one position until sufficient material is volatilized from the bounding walls to cause extinction, but rather to cause arc movement over cool surfaces until the arc is extinguished. In the absence of arc movement, an arc playing against a hard fiber surface such as is suitable for the filler and tube of my invention, evolves gases which are largely hydrogen and oxides of carbon, which are the result of destructive distillation, and evidenced by grooving and erosion. With rapid arc movement, the heat of the arc does not have time to penetrate much below the surface, water vapor is evolved to cause the desired arc movement to extinction, and replacing moisture subsequently reabsorbed from the atmosphere, thus eliminating the erosion which accompanies the operation of many types of expulsion devices. It will be apparent from the above considerations that a construction in which arc movement is greatest for a given size of device is most advantageous.

These and other objects and advantages will be more apparent from the following description of the accompanying drawing which illustrates a specific embodiment of my invention, and the scope of the invention will be indicated by the appended claims.

In the drawing: Fig. 1 is a longitudinal view of an arc interrupter constructed according to the principles of my invention, shown partly in section; Fig. 2 is a section along the line II—II of Fig. 1; and Fig. 3 is a view of the lower end of the lower end of the arc interrupter. In addition to the several views of the interrupter, Fig. 4 has been included to illustrate a fragmentary development of the inner bounding surface of the arc space, showing successive positions taken by an imaginary arc from inception to extinction.

The arc interrupter illustrated in Figs. 1, 2, and 3 comprises the longitudinally extending tube of insulating material 18, to the upper end of which is suitably fastened, as by screw threads, the metal cap 13, the latter providing both a closure for the upper end of the tube and a conducting electrode extending over the arc chamber from the upper conducting terminal member 12. The leakage gap indicated at the numeral 11, in accordance with usual practice, is interposed between the terminal member 12 and the conductor 10, the voltage of which it may be desired to limit to some predetermined amount. The conducting cap 20 threadedly engages the lower end of the tube 18, and for reasons later to appear, is provided with the vent 21, the latter extending only partially around and in registration with the inner periphery of the tube 18. The lower conducting terminal member 22 extends upwardly in threaded engagement through the lower cap 20, and downwardly therefrom, and to the downwardly extended portion the mounting bracket 26 (partially shown), and the conductor 25 are fastened, respectively by means of the terminal nuts 23 and 24. As shown in Fig. 1, the arc interrupter is in position to discharge excessive voltages appearing between the conductor 10 and the conductor 25.

The filler 15, of insulating material, extends longitudinally in and is contained by the tube 18. The respective ends of the filler 15 are provided with inwardly extending recesses into which are respectively extended the upper terminal member 12 and the lower terminal member 22, the resilient bushing 14, of live rubber or other suitable material, being interposed between the outer surface of the downwardly extended portion of the terminal member 12 and the wall of the recess at the upper end of the filler 15, and the resilient bushing 19, at the lower end of the filler 15, is similarly arranged with respect to the terminal member 22.

The members just described are so arranged that the filler 15 is held in lateral abutting engagement with the inner surface of the tube 18 along an abutment line, as shown in Fig. 2, and the unoccupied space between the tube and filler provides the arc space of the construction. As may be noted by inspection of Fig. 2, the longitudinally extending path of minimum divergence of the inner wall of the tube 18 with respect to the outer surface of the filler 15 is along the abutment line, and that of maximum divergence is displaced peripherally from the abutment line by an angle greater than 180 degrees. To establish a predetermined sparkover path through the device, the initiating electrode constituted by the conducting members 16 and 17 is provided. The member 16 extends upwardly through the filler 15 toward and in spaced relation with the upper electrode 13, contacting at its lower end the lower terminal member 22, and at its upper end the inner end of the radially extending member

17. The outer end of the member 16 terminates at the outer surface of the filler 15, at a point offset from the abutment line, peripherally between the paths of minimum and maximum divergence, and in longitudinal spaced relationship with the upper electrode 13. The spacing of the electrode 17 from the upper electrode 13 is the shortest distance between the conducting elements associated respectively with the upper and lower ends of the tube 18, and is thereby established as the weakest electrical path over which sparkover is caused to occur. Both the filler 15 and the tube 18 are preferably of some material having resistance to heat, and ability to evolve cooling gas in the presence of an arc. Hard fiber is the best material I have so far discovered for this purpose.

From an inspection of Fig. 2 it will be apparent that the path of maximum divergence is peripherally displaced more than 180 degrees from both the electrode 17 and the line of abutment by forming the peripheral surface of the filler in the form of a spiral. This construction illustrates, as compared with other constructions known to me, the much longer peripheral distance which an arc may be caused to traverse, in a given size structure, by the use of my invention.

The operation of my invention may be clearly explained in connection with Fig. 4. When a predetermined difference of potential between the respective normally insulated conducting members 13 and 20 occurs, sparkover is caused over the weakest electrical path, this sparkover being indicated by the longitudinally extending line 40 designated by the letter *a*, and extending from the initiating electrode 17 and the point 28 on the upper electrode 13. Gas evolution immediately accompanies the discharge. The abutment line prevents movement of gas toward the abutment line, and gas movement occurs in the direction of the arrows of Fig. 5. The arc is carried along with the gas through the successive positions indicated at *b*, *c*, *d*, and *e*. At the latter position, because of approach to the abutment line from the opposite direction, the gas is caused to move substantially longitudinally through the arc to the vent 21, resulting in maximum contact of the gas with the arc, which is a condition for effective extinguishment. The desired movement 45 of the gas is facilitated by positioning the vent longitudinally under the path of least restriction, as illustrated.

It will be apparent that the impact caused by large discharges of lightning current is cushioned 55 in my invention by causing sparkover to occur through the air space between the insulating elements, and that the discharge tends to roll the filler along the inner surface of the tube, rather than blasting it directly away from the abutment line. It may be further noted that great flexibility of design is possible through the principles exemplified by my invention, by adjustment of the position of the sparkover path and of that of the vent.

In the practical application of my invention, best results are obtained by using larger diameters of tube and filler than are usually found in common practice. Usual filler diameters are of the order of one-half of one inch. Such diameters are insufficient to provide the necessary peripheral length of arc travel to obtain best operation and avoid substantial erosion. In practice, 100% elongation of arc with $1\frac{1}{4}$ inches of peripheral movement, using $\frac{1}{8}$ inch fillers and $\frac{3}{4}$ inch tubes, with a length adjusted to the

voltage to be interrupted, has given fair results. Much better results have been obtained using fillers of about 1½ inch diameter in 1 $\frac{1}{16}$ inch tubes, thus doubling the peripheral arc movement.

Many modifications and changes in my invention will be apparent from the description herein, and it is intended that this description will be regarded as illustrative, rather than limiting.

I claim as my invention:

1. A voltage-limiting arc interrupter comprising insulating members including a longitudinally extending tube vented at one end thereof and a filler therein partially closing the bore of said tube, conducting terminals mounted at the respective ends of said tube, means holding said filler in lateral abutting relation with the internal surface of said tube along a single longitudinally extending abutment line to provide between the inner surface of said tube and the outer surface of said filler a single undivided curved arc space which extends entirely around said filler, the distance between the outer surface of said filler and the inner surface of said tube continuously increasing peripherally from said abutment line to a line parallel thereto and peripherally spaced more than 180 degrees therefrom, and structural means for causing sparkover to occur longitudinally along said filler within said arc space over a predetermined line between said abutment line and said peripherally spaced line, said structural means including conducting electrodes mounted in longitudinally spaced normally insulated relationship along said arc space and so coordinated with said insulating members that said predetermined line is the weakest electrical path within said tube between said terminals.

2. A voltage-limiting arc interrupter comprising insulating members including a longitudinally extending tube vented at one end thereof and a filler therein, said filler having a smaller cross-sectional area than that of the bore of said tube, conducting terminals mounted at the respective ends of said tube, means holding said filler in lateral abutting relation with the internal surface of said tube to provide therebetween a single undivided curved arc space which extends longitudinally over the length of said filler and peripherally more than one-half the distance around said filler, the divergence of the outer surface of said filler with respect to the inner surface of said tube continuously increasing peripherally from said abutment line to a peripherally spaced line parallel thereto and more than 180 degrees therefrom, and structural means for causing sparkover to occur longitudinally along said filler within said arc space over a predetermined line between said abutment line and said peripherally spaced line, said structural means including conducting electrodes mounted in longitudinally spaced normally insulated relationship along said arc space and so related to said insulating members that said predetermined line is the weakest electrical path within said tube between said terminals.

3. A voltage-limiting arc interrupter comprising insulating members including a longitudinally extending tube vented at only one end thereof and a filler contained by said tube, said filler having a smaller cross-sectional area than that of the bore of said tube, conducting terminals mounted at the respective ends of said tube, means holding said filler in lateral abutting relation with the internal surface of said tube to provide therebetween a single undivided curved

arc space which extends longitudinally over the length of said filler and peripherally more than one-half the distance around said filler, the divergence of the outer surface of said filler with

5 respect to the inner surface of said tube continuously increasing peripherally from said abutment line to a peripherally spaced line parallel thereto and more than 180 degrees therefrom, and structural means for causing sparkover to occur longitudinally along said filler within said arc space over a predetermined line between said abutment line and said peripherally spaced line, said structural means including conducting electrodes mounted in longitudinally spaced normally insulated relationship along said arc space, one of said electrodes extending inwardly into said arc space from that conducting terminal at the vented end of said tube to a point at one end of said predetermined line whereby the latter is established as the weakest electrical path between said terminals.

10 4. A voltage-limiting arc interrupter comprising insulating members which evolve gas in the presence of an arc, said insulating members including a longitudinally extending tube and a filler therein, said filler having a smaller cross-sectional area than that of the bore of said tube, conducting terminals mounted at the respective ends of said tube, means holding said filler in lateral abutting engagement with the internal surface of said tube to provide therebetween a single undivided arc space which extends longitudinally over the length of said filler and peripherally more than 15 one-half the distance around said filler, the divergence of the outer surface of said filler with respect to the inner surface of said tube continuously increasing peripherally from a minimum at said abutment line to a maximum at a peripherally spaced path parallel thereto and more than 180 degrees therefrom, and structural means for causing sparkover to occur longitudinally along said filler within said arc space along a predetermined line between said abutment line and said peripherally spaced path, said structural means including conducting electrodes mounted in longitudinally spaced normally insulated relationship along said arc space and so related to said insulating members that said predetermined line is the weakest electrical path between said terminals, and a vent opening directly into that position of said arc space having maximum divergence.

20 5. A voltage-limiting arc interrupter comprising insulating members which evolve gas when subjected to the heat of an arc, said insulating members including a longitudinally extending tube and a filler contained by said tube, said filler having a smaller cross-sectional area than that of the bore of said tube, conducting terminals mounted at the respective ends of said tube, means holding said filler in lateral abutting relation with the internal surface of said tube to provide therebetween a single undivided arc space 25 which extends along said filler and peripherally more than one-half the distance around said filler, the divergence of the outer surface of said filler with respect to the inner surface of said tube continuously increasing peripherally from a minimum along said abutment line to a maximum along a parallel path peripherally spaced more than 180 degrees therefrom, said tube being closed at one end and provided with a vent at the other end, said vent being located in longitudinal alignment with that portion of said arc

space having maximum divergence, and structural means for causing sparkover to occur longitudinally along said filler within said arc space over a predetermined line between the line of minimum divergence and the peripherally spaced path of maximum divergence, said structural means including conducting electrodes mounted in longitudinally spaced normally insulated relationship along said arc space, one of said elec-

trodes extending inwardly into said arc space from that conducting terminal at the vented end of said tube to a point at one end of said predetermined line whereby the latter is established as the weakest electrical path between said terminals.
